UNITED STATES PATENT OFFICE.

ARTHUR BARING-GOULD, OF PLACERVILLE, CALIFORNIA.

SHIP PROPULSION.

1,315,620.

Specification of Letters Patent.

Patented Sept. 9, 1919.

Application filed April 29, 1918. Serial No. 231,468.

To all whom it may concern:

Be it known that I, ARTHUR BARING-GOULD, a subject of the King of Great Britain, residing at Placerville, in the county of Eldorado and State of California, have invented certain new and useful Improvements in Ship Propulsion; and I do declare the following to be a full, clear, and exact description of the same, reference being had to the accompanying drawings, and to the characters of reference marked thereon, which form a part of this application.

This invention relates to improvements in means for propelling ships of all types through the water. This is now commonly done by a small screw propeller arranged at the stern of the ship. By my improved invention, I aim to augment this system of propulsion by having a series of elongated screw propellers arranged along the entire keel of the ship and driving them with a worm drive so as to have no lost motion or undue vibration or noise.

A further object of the invention is to produce a simple and inexpensive device and yet one which will be exceedingly effective for the purposes for which it is designed.

These objects, I accomplish by means of such structure and relative arrangement of the parts as will fully appear by a perusal of the following specification and claim.

On the drawings, similar characters of reference indicate corresponding parts in the several views.

Figure 1 is a side elevation of a boat showing my improved propellers thereon.

Fig. 2 is a sectional view of the boat showing the driving means for my improved propellers.

Referring now more particularly to the characters of reference marked thereon, the numeral 1 designates the ship or boat, which may be of any type desired.

My invention consists of approximately three elongated screw propellers 2, 3 and 4 arranged end to end along the keel of the boat, such propellers having suitable bearings within housings 5 at which points they are provided with pinions 6. Each pinion 6 intermeshes with worm gears 7 and 8 on shafts 9 and 10 which project into the hull of the boat. On the opposite ends of the

shafts 9 and 10 are beveled gears 11 and 12 which intermesh with beveled gears 13 and 14 on shafts 15 and 16.

55

The numeral 17 designates the main driving shaft for all of the propellers which in turn drive worm gears 18 meshing with pinions 19 on stub shafts 20. Each stub shaft is arranged to be placed into or out of driving relation with the shafts 15 and 16 by means of suitable clutches 21 and 22 for imparting forward or reverse motion to the propellers 2, 3 and 4.

60

For steering the boat, the central propeller 65 may be driven in one direction and either of the others in the opposite direction, which will cause the boat to pivot. This feature will be especially advantageous in a time of war when it is desirous of having the ship 70 make a quick turn to avoid being struck by torpedoes.

It will be readily apparent to those skilled in the art that my improved elongated screw propellers will, driven as they are by worm 75 driving connections, impart a smooth, swift, easy gliding motion to the boat or ship, enabling the same to make much greater speed through the water with a relative minimum amount of vibration of tossing on the waves 80 of the water.

From the foregoing description it will readily be seen that I have produced such a device as substantially fulfills the objects of the invention as set forth herein.

85

While this specification sets forth in detail the present and preferred construction of the device, still in practice, such deviations from such detail may be resorted to as do not form a departure from the spirit of the 90 invention as defined by the appended claim.

Having thus described my invention, what I claim as new and useful and desire to secure by Letters Patent is:—

The combination with a ship, having a 95 plurality of elongated propellers placed in a line beneath the keel thereof, of a common drive means for all the propellers and independent means for each propeller whereby the same may be stopped or reversed, such 100 means including a longitudinal power driven shaft common to all the propellers, a transverse shaft for each propeller in driving relation with the power shaft, a pair of verti-

cal shafts arranged in reverse driving relation with the propeller from the corresponding transverse shaft, a clutch on the transverse shaft for each vertical shaft and arranged to transmit power therebetween, and a clutch operating means common to both clutches whereby when one clutch is disconnected the other may be simultaneously thrown in to stop one of the vertical

shafts and start the other to reverse the direction of motion of the propeller.

In testimony whereof I affix my signature in presence of two witnesses.

ARTHUR BARING-GOULD.
